UNITED STATES PATENT OFFICE

JOHN V. ABRONSKI, OF PITMAN, NEW JERSEY

WINDOW SCREEN

Original application filed October 10, 1927, Serial No. 225,100. Divided and this application filed May 22, 1929. Serial No. 365,046.

The present invention relates to screens for windows and the like and comprises matter divided out of my application, Serial No. 225,100, filed October 10, 1927, for a window screen.

An object of the invention is to provide a screen frame having the means for clamping the screen fabrics therein and slide members out of a single sheet of metal strip.

10 A further object is to provide a screen frame with a compensating strip which may be cut to conform with misalignments in the window frame.

The invention contemplates a frame 15 for holding wire cloth or the like in a window opening having associated with the various parts thereof strips of metal, bent in a manner to hold and stretch screen material thereto and providing a slide or side 20 flange which may be sheared off to compensate for misalignment in the window frame resulting from the settling of the building or from other similar causes; the holding members and the compensating flange being 25 formed integrally with a body portion.

These metal strips may constitute the frame members themselves or may comprise a sheathing for filler members constituting therewith the frame members.

30 In the drawings:—

Figure 1 illustrates a window frame representing the same as being out of plumb with a window screen made in accordance with the present invention positioned therein,

35 Figure 2 is a section on the line 2—2 of Figure 1 showing the connection of a side frame member to the slideway in the window frame,

40 Figure 3 is a section on the line 3—3 of Figure 1 showing the manner of connecting the screen material to the top and bottom rails of the screen frame; Figures 2 and 3 are on an enlarged scale compared with Figure 1,

45 Figure 4 shows the manner of connecting the screen material to top and bottom frame members made entirely of a metal strip, and

50 Figure 5 is a similar construction for the side frame members, these views showing the structures fragmentarily and showing the construction thereof; Figures 4 and 5 are on

a further enlarged scale compared with Figures 2 and 3.

Figures 1, 2 and 3 show one form of the screen construction in which there is a frame comprised of frame members 10 of wood or other fibrous material covered with a metal sheathing 11 surrounding the fibrous filler and adapted as will hereinafter be set forth to hold the screen 12 clamped therein, the construction of the sheathing being such that the securing of the screen to the frame is accompanied by a simultaneous stretching thereof. The sheathing is so constructed as to perform a plurality of functions and to provide the several parts advantageously to 60 the clamping of a screen to the frame and the mounting of the frame in a window casing from a single unitary sheet of material.

In the form of frame illustrated in Figures 2 and 3, the fibre filling 10 is surrounded, as stated above, by a sheathing which is provided with a flange 13 on one edge thereof, a portion 14 extending at right angles thereto and bent over the filler at 15 providing a body portion 16 adjacent one end of 65 which is a rib or flange 17 provided by rebending the material upon itself.

In spaced relation to this rib and adjacent the other side of the body portion 16 is a clamping member 18 formed in the same manner. This clamping member is bendable and, as shown in Figures 2 and 3, is bent down into parallelism with the body portion in order to clamp the screen material 12 between said clamping member and the body portion. To 70 toward the free end of the clamping member the same may be bent upwardly, as at 19, in parallelism with the flange 17, after which it may be bent again to parallelism with the body portion 16 to overlap the flange 17.

The material beyond the flange 17, progressing around the filler in a clockwise direction, as shown in Figure 2 of the drawings, is extended downwardly in contact with the filler, as shown at 20, and then rearwardly on the opposite face thereof to the body portion, as at 21, being rebent upon itself, as at 22, to form a connection with the flange 13 referred to above. The material may then be reversely bent, as at 23, and then down- 75 80 85 90 95 100

wardly, as at 24, and laterally to form a slide flange 25.

The flange 25 may be slidingly housed in the slideway designated as a whole at 26 which is formed by bending a further sheet of material upon itself in the following manner. A flange 27 is provided at right angles to which are formed by bending the metal upon themselves a pair of spaced members 28 and 29 forming therebetween a slideway. The metal is then bent at right angles, as shown at 30, and is rebent upon itself over the end of the flange 27 providing a surface 31 to be secured against a bead of the window frame.

The top and bottom rails of the window frame may be similarly encased by a metal strip, as shown in Figure 3 of the drawings, this strip having a flange 32 formed on one edge thereof and the other edge being rebent upon itself to overlap this flange, as shown at 33. The metal is continued from this portion 33 around the edge of the filler 10 and downwardly, as at 34; across the inner face 25 of the rail, as at 35, and upwardly across the edge as at 36. On the face to which the screen material 12 is attached, the casing is formed with a clamping member 18^a similar in all respects to the clamping member 18 shown in Figure 2.

In assembling the screen material to the frame after the members 10 have been encased in the sheathing and the portions 17 and 18 formed thereon, the screen is laid on top of the frame so as to rest upon the flanges 17 and 33 whereupon the clamping members are pressed downward upon this screen material and the overhanging portions for the flanges 17 and 33 are formed thereon. The members 25 may be cut to provide a snug fit in the slideways and to conform to any deformity of the window frame due to settling of the building or other causes.

In Figures 4 and 5, as stated above, are represented top, bottom and side frame constructions in which the member 10 is omitted. The representation in Figure 4 illustrates the top and bottom construction and consists of a sheet of metal bent upon itself to hold the edge of the screen. The bending of this metal may be as follows:

The metal may be rebent upon itself adjacent both edges, as shown at 37 and 38. The metal may be bent over the raw edge of one of these portions at right angles thereto, as shown at 39 and 40, the end of the portion 37 being connected with the portion 40 by a portion 41 lying in parallelism with the portion 39, as clearly illustrated in the drawings.

It will be noted that in this construction no raw edges of metal are encountered as these edges are both folded inwardly against the screen material.

A representation of the side frame mem-

bers is shown in Figure 5 which consists of a flange 42 at right angles to a body portion 43, a clamping portion 44 formed at the opposite edge of the body portion to the flange 42 by rebending the metal upon itself, the clamping portion being bent upwardly, as at 45, and then over the flange 42, as at 46.

The material is then bent rearwardly, downwardly, then rearwardly and partly overlapping the edge 47 after which it is extended laterally of the screen frame to provide a slide flange 48. This flange, it will be noted, is cut from a much wider flange which may be provided and is shown in dotted lines at 49, the cutting being made at such an angle as the situation may require in order to fit in slideways out of line with the vertical.

The slideway of a frame made in accordance with the showing in Figures 4 and 5 may be of the same character as that illustrated in Figure 2 of the drawings.

It will be understood that the embodiments set forth hereinbefore and shown in the drawings are merely illustrative of the invention and may be changed in various details without departing from the spirit of the invention hereinbefore set forth and herein-after claimed.

Having thus described my invention, what I claim is:

1. A screen frame member comprising in integrality a fabric engaging ledge; and a compensating flange adapted to be trimmed to reduce the overall width of the member.

2. A screen frame member comprising in integrality a fabric engaging ledge with an adjacent fabric receiving depression; and a compensating flange adapted to be trimmed to reduce the overall width of the member.

3. A screen frame member comprising in integrality a fabric engaging ledge; and a rigid compensating flange adapted to be trimmed to reduce the overall width of the member.

4. A screen frame member comprising in integrality a fabric engaging ledge; and a rigid flange comprising a single thickness of material adapted to be trimmed to reduce the overall width of the member.

5. A screen frame member comprising in integrality a fabric engaging ledge with an adjacent fabric receiving depression, and a laterally extending rigid compensating flange adapted to be trimmed to reduce the overall width of the member.

6. A screen frame having upon remote sides compensating flanges lying in some of the major planes of the screen and adapted to be trimmed to reduce the overall size of the screen to required fitting proportions.

7. A screen frame having upon remote sides laterally extending compensating flanges comprising each a single thickness of material lying in some of the major planes of the

screen and adapted to be trimmed to reduce the overall size of the screen to required fitting proportions.

8. A screen frame having upon remote sides rigid compensating flanges comprising each a single thickness of material lying in some of the major planes of the screen and adapted to be trimmed to reduce the overall size of the screen to required fitting proportions.

10. In testimony whereof I have signed my name to this specification.

JOHN V. ABRONSKI.
